POWER TAKE-OFF FOR CHAIN SAWS

Robert B. Huxtable, 4109 W. Saginaw,
Lansing, Mich. 48917

Filed Mar. 13, 1967, Ser. No. 6,204

Term of patent 14 years

(Cl. D55—1)

FIG. 1

FIG. 3

FIG. 6

FIG. 4

FIG. 5

FIG. 2

FIGURE 1 is a perspective view of a power take-off for chain saws showing my new design;
 FIGURE 2 is a left side elevational view thereof;
 FIGURE 3 is a bottom view thereof;
 FIGURE 4 is a rear elevational view thereof;
 FIGURE 5 is a right side elevational view thereof; and
 FIGURE 6 is a top plan view thereof.

The broken line representation of a chain saw in FIGURE 1 is for purposes of illustration only.

I claim:

The ornamental design for a power take-off for chain saws, as shown and described.
